UNITED STATES PATENT OFFICE.

GEORGE W. MCGILL, OF BUFFALO, NEW YORK.

IMPROVED DOOR-FASTENER.

Specification forming part of Letters Patent No. 19,937, dated April 13, 1858.

To all whom it may concern:

Be it known that I, GEORGE W. MCGILL, of the city of Buffalo, in the county of Erie and State of New York, have invented a new and Improved Mode of Fastening Doors, whether opening from without or from within; and I do hereby declare that the following is a full and exact description thereof, reference being had to the accompanying drawings, and to the letters of reference marked thereon.

The nature of my invention consists in the construction of a door-fastener which may be conveniently carried about one's person as a substitute for locks, bolts, &c., and which can be attached to any description of door, whether opening in or from a room, without difficulty.

To enable others skilled in the art to make and use my invention, I will proceed to describe its construction and operation.

Figure 1 in the accompanying drawings represents the article closed. Fig. 2 represents the fastener as applied to a door which opens out from a room.

The teeth *a a* on the crooked blade *B* are pushed into the door *Z*. The thumb-screw *C* is then drawn into the socket *d* and the door is pulled to. Blade *B* being shaped to

the jamb of the door allows it to shut. The gimlet-pointed screw *C* is then screwed into the jamb and the door is secure; but should the door open into a room the teeth *H H* on blade *I*, Fig. 3, are pushed into the jamb of the door *K*. The thumb-screw *L* is screwed to one side and the door is closed. The thumb-screw *L* is then screwed out across both jamb and door and secures the door from being pushed in.

The blades *B* and *I* are secured together by the socket *d*, and the flange *O* on the thumb-screw *C* holds it in the socket *d*.

Having thus fully described the nature, construction, and operation of my invention, I will now proceed to state what I claim and desire to secure by Letters Patent:

1. The formation of blade *B*, with its peculiar connection with blade *I*.
2. The use of the blade *B*, constructed as described and operating in connection with screw *L* and blade *I* and screw *C*, for the purpose specified.

GEORGE W. MCGILL.
